UNITED STATES PATENT OFFICE

FREDERICK DAVE CHAPMAN, OF EVANSTON, ILLINOIS, ASSIGNOR TO THE HARRINGTON & KING PERFORATING COMPANY, OF CHICAGO, ILLINOIS, A CORPORATION OF ILLINOIS

DESIGN FOR A GRILLE PANEL UNIT

Application filed May 16, 1931. Serial No. 39,865. Term of patent 14 years.

To all whom it may concern:

Be it known that I, FREDERICK DAVE CHAPMAN, a citizen of the United States, residing at Evanston, in the county of Cook and State of Illinois, have invented a new, original, and ornamental Design for a Grille Panel Unit, of which the following is a specification, reference being had to the accompanying drawing, forming a part thereof.

In the drawing:

Figure 1 is a fragmentary detail face view

showing a single decorative unit of a design for the grille panel illustrated in Figure 2.

Figure 2 is a fragmentary face view of a grille panel embodying this design, but showing a larger portion of the panel than Figure 1.

I claim:

The ornamental design for a grille panel unit substantially as shown and described.

F. DAVE CHAPMAN.
